O. KLEIN.
SELF INDICATING TARGET.
APPLICATION FILED JUNE 8, 1912.

Patented Sept. 9, 1913.

UNITED STATES PATENT OFFICE.

OTTO KLEIN, OF PATERSON, NEW JERSEY.

SELF-INDICATING TARGET.

1,072,621.

Specification of Letters Patent. Patented Sept. 9, 1913.

Application filed June 8, 1912. Serial No. 702,463.

To all whom it may concern:

Be it known that I, OTTO KLEIN, subject of the German Emperor, residing at Paterson, in the county of Passaic and State of New Jersey, have invented certain new and useful Improvements in Self-Indicating Targets, of which the following is a specification.

The present invention relates to targets and has for its object to provide such a construction that the distance of the shot mark from the bull's eye will be automatically indicated.

To make my invention more clear the same is illustrated in the accompanying drawing in which similar reference letters denote corresponding parts and in which

Figure 1 is a front elevation of the target; Fig. 2 a perspective view of a part of the target illustrating the working thereof and Fig. 3 a vertical central section of the target.

In the drawing, which forms a part of this specification, *a* denotes a box or casing of rectangular cross section in which the target proper is arranged and which has an open front adapted to be normally closed by a cover *b* which is provided with a circular hole *b'* of a size corresponding with that of the target disk.

The target proper consists of a circular metal disk *C* composed of a number of individual concentric parts *c'*, *c²*, *c³*, *c⁴* and *c⁵* which form the separate sections. These concentric parts are freely movable rearwardly and independently from one another and are each independently suspended from the upper wall of the box in the following manner: Fastened in the upper wall of the box and arranged parallel to one another in a central vertical plane are two rods *d* or the like which extend downwardly through the casing. Secured above one another in a vertical central plane to each individual part of the target disk *C* at the upper and lower portions thereof are horizontal slotted arms *e* or the like which project rearwardly and which movably engage the parallel vertical rods *d* forming thus guide members. Secured to the lateral portions of each ring and arranged in a horizontal central plane are rearwardly extending arms *f* of which each is provided with two eyelets *f'*, one arranged at the forward and the other at the rearward end thereof. Secured to the upper wall of the casing parallel to

one another and to the plane in which the rods *d* are located are bars *g* or the like which are formed with ear-laps or eyes *g'*. The bars *g* are arranged in vertical planes with the respective horizontal arms *f* and the eyes *g'* thereof are in line with the eyes *f'* of the respective arm *f*. Freely engaging the opposite eyes *f', g'* are rods *h* formed at each end with a hook. By these means each ring is centered and so suspended from the upper wall of the box, as to be capable of a short swinging motion. The lateral arms of each individual ring of the target disk carry counterweights *i* which tend to maintain the ring in its forward central position. The section *c'* which serves as the bull's eye is formed of a solid circular disk and is movably suspended from the upper wall of the casing in a similar manner as the rings surrounding it, with that exception, that instead of having two slotted arms, a single slotted arm *j* projects centrally from the rear wall thereof, which, as the slotted arms of the surrounding rings, embraces as a guide the parallel vertical rods *d*.

At a suitable point below the target disk a spindle *k* is provided which extends transversely through the casing and may be journaled in the side walls of the latter. This spindle carries a number of angular plates *l* which are rotatively mounted thereon and the number of which corresponds to that of the sections of the target disk. The outer surface of the lower bend *l'* of each angular plate *l* has printed, embossed or otherwise arranged thereon a figure or character *m* whereby the distance or the number of the section from the bull's eye may be determined. Normally, that is when the individual rings are in their forward position, the angular plates are adapted to occupy such a position that the lower bends *l'* carrying the figures or characters *m* are raised, rendering the figures non-visible. In this position each plate is supported by a bar *n* which is rigidly secured to and projects downwardly from one of the lateral arms *f* of the respective ring of the target disk. To this end the lower portion *n'* of the bar *n* is cam or hook-shaped and forms a rest for the lower bend *l'* of the angular plate *l*. When, while shooting, a section is struck, the latter is caused to slightly swing rearwardly, whereby the hooked bar *n* is withdrawn from the respective number plate,

releasing the latter, which, by its own weight, will be caused to swing around the spindle k so that the lower bend l^a will come into the dotted position (Fig. 2), exposing the number m . The cover b is provided at its lower portion with a transversely extending slot b^2 through which the figures m may be visible. Immediately after the section is struck the same will be returned into its normal or forward position by its counterweights i bringing back the hooked bars n into their initial position in which they can engage the respective number plates. To return the number plates l into normal position, that is to say into engagement with the hooked bars n , a yoke-shaped member o or the like is rotatively mounted on the spindle k and extends across the space between the bends of the number plates l . Fulcrumed to the back wall of the casing is a weighted lever arm p to the free end of which is secured a cord g , wire or the like, which is guided over a sheave r and being wound around the member o is passed outwardly through a hole b^3 in the cover b of the casing. By the counterweighted lever p the member o normally will be swung rearwardly and downwardly so as to be out of contact with the number plates. The latter thus are allowed to freely swing around the spindle k when released from their respective hook-shaped supports n^a . When it is desired to return the number plates into normal or raised position the cord g is pulled outwardly, whereby the member o is brought to engage the upper bends of the member plates swinging the latter forwardly until the lower bends l^a thereof are raised onto their respective supports n^a , as indicated by full lines in Fig. 2.

The mode of operation is as follows: The individual sections composing the target normally occupy a forward position, all lying in a vertical plane. In this position the number plates are raised so that the numbers m are not visible through the recess b^2 . When, while shooting, any one of the sections is struck, as for instance, the ring c^5 (Fig. 2), the latter is caused to slightly swing rearwardly whereby the hook-shaped bar n releases the plate l and permits it to swing by its own weight downwardly, so that the figure m on the outer face of the lower bend l^a will appear in the slot b^2 (Fig. 1). While the ring c^5 after the shot by its counterweights i is caused to immediately return into its initial position, the respective number plate remains in the lifted position and can be

raised and brought into engagement with the support n^a by pulling the cord or wire in the aforescribed manner.

It is understood that the construction may be modified in various ways without departing from the principle of my invention, and I, therefore, do not restrict myself to the details described and shown.

What I claim and desire to secure by Letters Patent is:

1. A target composed of individual concentric and independently movable sections, a swinging counter-balanced parallel motion mechanism for each of said sections and with which each section is suspended and means coöperating with said movable sections and adapted to indicate the section struck.

2. A target composed of individual, concentric and independently movable sections, a swinging counter-balanced parallel motion mechanism for each of said sections and with which each section is suspended, stationary guide members common for all said sections, guideways on each section coöperating with said stationary guide members and means coöperating with said sections and adapted to indicate the section struck.

3. In a target, a target disk composed of individual, concentric and independently movable sections, a swinging counter-balanced parallel motion mechanism for each of said sections and with which each section is suspended, a tiltable indicator for each section, and a member connected to each parallel motion mechanism and coöperating with the corresponding indicator so as to release the latter when the corresponding section is struck.

4. In a target, a target disk composed of individual, concentric and independently movable sections, a swinging counterbalanced parallel motion mechanism for each of said sections and with which each section is suspended, a tiltable and gravity operated indicator for each section, a member connected to each parallel motion mechanism and normally supporting the corresponding indicator and a manually operated mechanism common for all indicators to return the tilted indicator into normal position.

In testimony whereof I affix my signature in presence of two witnesses.

OTTO KLEIN.
